UNITED STATES PATENT OFFICE.

WILLIAM L. JUHRING, OF BROOKLYN, NEW YORK.

DESIGN FOR A BOTTLE.

SPECIFICATION forming part of Design No. 34,318, dated April 2, 1901.

Application filed March 7, 1901. Serial No. 50,272. Term of patent 7 years.

To all whom it may concern:

Be it known that I, WILLIAM L. JUHRING, a citizen of the United States, and a resident of Brooklyn, county of Kings, and State of New York, have invented a new and original Design for Bottles, of which the following is a specification, reference being had to the accompanying drawings, in which—

Figure 1 is a side elevation of my newly-
designed bottle; and Fig. 2 is a cross-section
on line 2 2, Fig. 1.

The leading feature of my design consists
of a bottle having a body that tapers from
top to bottom and is corrugated longitudi-
nally, as at *a*, the corrugations inclosing a

shield-shaped section *b*. At the bottom is formed a head *c* and at the top a concavo-convex section *d*, which is separated from the cylindrical neck *e* by a bead *f*.

What I claim is—

The design for a bottle, substantially as herein shown and described.

Signed by me at New York city, county and State of New York, this 6th day of March, 1901.

WILLIAM L. JUHRING.
